LIGHTING FIXTURE

Edwin F. Guth, Florissant, Mo.

Application January 30, 1946, Serial No. 624,324

2 Claims. (Cl. 240—51.11)

1

This invention relates to lighting fixtures, and more particularly to lighting fixtures for tubular lamps.

Among the objects of this invention are the provision of lighting fixtures for tubular lamps, which are recessed into walls or ceilings; the provision of lighting fixtures of the type described which are of standard size and may be used in multiple units; and, the provision of lighting fixtures of the type indicated which, while of standard size to accommodate standard size tubular lamps, also are of an over all dimension to fit standard building construction units. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a vertical section through a lighting fixture embodying the invention;

Fig. 2 is an end elevation of the fixture;

Fig. 3 is a section on an enlarged scale taken on line 3—3 on Fig. 2;

Fig. 4 is a section taken on line 4—4 on Fig. 1;

Fig. 5 is a bottom plan of the right end of the Fig. 1 structure;

Fig. 6 is a top plan of the lighting fixture;

Fig. 7 is a diagrammatic view showing two sockets with a tubular lamp in place;

Fig. 8 is a diagrammatic view showing a top plan of the light fixture; and,

Fig. 9 is a diagrammatic view showing three units mounted together.

Similar reference characters indicate corresponding parts throughout the several views of the drawings.

There has been a constant trend toward standardization of construction materials. This makes building and installation easier and less costly. This tendency extends to lighting fixtures as well as to construction materials customarily used with them. For example, tubular lighting fixtures are frequently recessed into ceilings and walls. The surfaces of such ceilings or walls are frequently of sound insulating material, which is customarily made and installed in units which are 12 inches or 24 inches in length. Lighting fixtures for fluorescent and other tubular lamps are customarily

2

48 inches in length from the outer edge of one socket to the outer edge of the other.

However such lighting fixtures for fluorescent and other tubular lamps customarily have end plates outside of the sockets. Such end plates occupy a material amount of room since they are at least $\frac{1}{16}$ inch thick. Lighting fixtures for lamps, such as fluorescent lamps, are frequently installed in multiple units. Where this is done a plurality of individual fixtures is installed end to end to form a larger fixture. When this is done the sum of the thicknesses of the end plates increases in accordance with the number of units employed. When a half dozen or more units are installed, and this is not an infrequent occurrence, they will not fit into the steel structure which supports acoustical panels nor can the panels be fitted in without special cutting and fitting. This greatly increases the cost and difficulty of installing such fixtures.

The present invention will be illustrated as applied to lighting fixtures for tubular fluorescent lamps. It will be understood however that it is also applicable to other types of tubular lamps.

Referring now to the drawings, numeral 1 represents a lighting fixture of the present invention. This fixture comprises a trough-shaped unit including a supporting channel 3 having end plates 5 attached to each end thereof. The channel 3 is mounted in inverted position with its base 7 uppermost and forming the top of the fixture. Supporting brackets 9 and 11 are attached to channel 3. The customary electrical equipment is supported within channel 3.

Brackets 9 and 11 support the customary sockets 13 at either end of the structure within the trough. Bracket 11 has openings 15 for the usual fuse plugs (not shown). A cover 17 is mounted under the channel 3 to provide a reflecting surface in combination with side panels 19.

The fixture has the usual accessories such as ledges 21 for attaching the fixture to the wall or ceiling indicated generally at 23, notches 25 for the attachment of diffusers, and knockout plugs 27, 29 and 30 for the introduction of wiring. Threaded sockets 31 are provided for attaching the fixture by suspension if that is preferred.

End plates 5 have areas 33 almost completely relieved therefrom and moved outward a distance equal to the thickness of end plates 5. These areas 33 are of the same configuration as sockets 13 and are located opposite thereto. Sockets 13 are in turn supported on brackets 9 and 11 fitting within the relieved areas 33 so that their outer surface is approximately parallel

with the outer surface of end plates 5. Sockets 13 are located the standard distance apart (for example 48 inches) so as to accommodate standard tubular fluorescent lamps.

Shield 17 is held in place removably by bolts 37 to permit easy access to the transformer and the other electrical equipment located in channel 3. Sockets 13 are held in place on brackets 9 and 11 by bolts 39.

Referring now to Figs. 7-9, an important advantage of the present construction is diagrammatically illustrated. Standard fluorescent lamps 35 are shown in place between sockets 13. In this way the over all distance between the outer surface of the sockets 13 may be regarded as X which in the illustration given above would be 48 inches. If we then let Y equal the thickness of the end plates it will be seen that the over all length of the fixture (see Fig. 8) will be $X+2Y$ where, as in the illustration given above, the end plates are $\frac{1}{8}$ of an inch thick, $X+2Y$ will equal 48 and $\frac{1}{8}$ inches. In this respect a single lighting unit of the present invention will occupy a space equal to the space customarily occupied by a standard fixture for tubular lamps if the areas 33 are left in place. In general it is preferred that these areas be left in place to meet the Underwriters' Laboratories, Inc. requirements and so as to prevent passage of undesired illumination through the sides of the fixture. Where such passage is not objectionable and where the sockets are not required to be covered the areas 33 may be easily and quickly removed merely by knocking them away from the fixture and the resulting fixture will then occupy merely the distance X (48 inches.)

However one of the most important advantages of the fixture of the present invention is illustrated in Fig. 9. Where a multiple unit assembly is to be installed in the customary way, that is by utilizing a series of fixtures located end to end in a long line, the areas 33 are knocked out in all of the end plates 5 except the end plates which will be exposed at either end of the multiple fixture. In this way it will be seen that such a multiple fixture does not increase the space occupied because of the presence of intervening end plates which otherwise add to the length of the entire multiple assembly. The only end plates to add to the length of the multiple unit are the exposed end plates at each end. In Fig. 9 for example, the total length of the multiple structure is $3X+2Y$ which is merely 3 times the unit length of the tubular lamps plus sockets, plus the thickness of two end plates. In previously known structures the length of such a multiple structure would not be $3X+2Y$ but $3X+6Y$.

The fixture of the present invention therefore may be recessed into a ceiling or wall composed of standard construction units such as acoustical panels without special cutting and fitting. Such a multiple fixture complies with the rules of the Underwriters' Laboratories, Inc. that no openings are permitted in the fixture larger than one inch and even these are restricted to certain locations on a fluorescent fixture. Many fixtures have been installed in the past in multiple assembly but even with a special very thin spider for connection the lamps are pinched tight and so do not fit into the regulation space between sockets.

These push-back knockout areas 33 protect the socket and live parts of the fixture during transportation and until installation. The fix-

ture meets the Underwriters' Laboratories, Inc. requirements and all fixtures may be manufactured alike using regular stock. No special dies or special equipment are required. Fixtures may be shipped complete with metal end plates intact and so installed. However where additional units are to be connected to make multiple installations, the steel socket plates 33 between units are merely knocked away from the rest of end plates 5. No special parts are required or special fixtures without end plates in order to make multiple installations. No special connection or spider section, as is generally used, is necessary with the fixtures of the present invention.

Although the knockout sections 33 are shown as having the same configuration as sockets 13, sections 33 need not be exactly so formed. They may be larger in area than socket 13 and of somewhat different configurations so long as they permit the outer surface of sockets 13 to be substantially aligned with the outer surface of end plates 5.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A lighting fixture for tubular lamps comprising a trough-shaped unit having an elongate lamp socket supporting member, side panels, and end plates, integral portions of the end plates adjacent the ends of the supporting member being outwardly relieved a distance approximating the thickness of the plates and constituting knockout portions, and a lamp socket mounted at each end of the supporting member, extending into the trough, and fitting within the relieved knockout portion of the respective end plate, the knockout portions having substantially the same configuration as the lamp sockets.

2. A lighting fixture for tubular lamps comprising a unit of inverted trough shape having a top, side panels, and end plates, integral portions of the end plates being outwardly relieved a distance approximating the thickness of the plates and constituting knockout portions, and a lamp socket mounted at each end of the unit fitting within the relieved knockout portion of the respective end plate and free of the knockout portion so that the latter may be removed if desired, said lamp sockets extending into the trough and being adapted to support a tubular lamp extending lengthwise in the trough, the knockout portions having substantially the same configuration as the lamp sockets.
